(57) **CLAIM**

The ornamental design for an ice shaver, as shown and described.

DESCRIPTION

FIG. 1 is a perspective view of an ice shaver showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view taken from alternative position;

FIG. 9 is the other perspective view taken from alternative position;

FIG. 10 is perspective view thereof shown in use; and,

FIG. 11 is another perspective view thereof shown in use. The broken lines in the drawings depict portions of the ice shaver that form no part of claimed design.

1 Claim, 11 Drawing Sheets
